UNITED STATES PATENT OFFICE

FRED E. NORTON, OF LYNN, MASSACHUSETTS, ASSIGNOR TO GENERAL ELECTRIC COMPANY, A CORPORATION OF NEW YORK.

EXTRACTING STEAM FROM STEAM-TURBINES.

1,091,078.

Specification of Letters Patent. Patented Mar. 24, 1914.

Application filed January 11, 1913. Serial No. 741,442.

To all whom it may concern.

Be it known that I, FRED E. NORTON, a citizen of the United States, residing at Lynn, county of Essex, State of Massachusetts, have invented certain new and useful Improvements in Extracting Steam from Steam-Turbines, of which the following is a specification.

This invention relates to steam turbines from which steam is extracted for industrial purposes after passing through one or more high pressure stages of said turbine. The amount of steam so extracted is liable to vary considerably from time to time, so that it is necessary to provide means for regulating the flow of steam through the turbine in order to maintain an approximately uniform pressure in the stage supplying the industrial appliances. The present invention has especial reference to mechanism for effecting such regulation. It comprises a valve controlling the passage of steam from the extraction stage of the turbine to the next stage of lower pressure, a motor for operating said valve; a movable abutment exposed on one side to the pressure of the steam in the extraction stage and on the other side to low or condenser pressure; a spring opposing the movement of said abutment, and a pilot valve for the motor controlled by said movable abutment. When the pressure in the extraction stage rises high enough to overcome the tension of the spring, the abutment moves and shifts the pilot valve to admit fluid pressure to the motor, which opens the valve between the stages and allows some of the steam to overflow into the next stage. This reduces the abnormal pressure in the extraction stage; conversely, if the extraction stage pressure drops too low, the motor will close the overflow valve and retain the steam in the extraction stage which causes its pressure to rise. In this way, a substantially constant pressure is maintained in the extraction stage.

In the accompanying drawings, Figure 1 is a side elevation of one end of a horizontal turbine equipped with my invention; Fig. 2 is an end view, partly broken away; Fig. 3 is a vertical section lengthwise of the motor and its valve mechanism; Fig. 4 is a horizontal longitudinal section of the pilot valve on the line 4—4, Fig.

3; Fig. 5 is a longitudinal section of a portion of the turbine on the line 5—5, Fig. 2, 55 and Fig. 6 is a cross section of the pilot valve but on a larger scale.

The turbine casing 1 has a high pressure steam-chest 2 containing the usual high pressure nozzle valves 2', which are controlled by suitable valve gear not shown. The casing has an outlet 3, Fig. 2, from a high pressure stage, preferably the first, said outlet being preferably cast integral with said casing, and connected to a conduit conveying steam from said stage to an industrial appliance such as a heating system, a dye kettle, a cooking device, or the like. Any steam not extracted through the outlet 3 passes through the lower stage 5, Fig. 5, of the turbine to the condenser conduit 6, Fig. 1. On the main shaft 7 are mounted the bucket wheels 8 and 9; the turbine illustrated being a two stage machine. The invention is applicable, however, to a turbine having any number of stages.

An annular flat-faced gridiron valve 10 controls the overflow of steam from stage 4 to stage 5, and is revolvable in a rabbeted ring 11 secured to the diaphragm 12 which separates the two stages and supports the nozzles 13 for the lower pressure stage. The overflow valve is operated by a rod 14 pivoted thereto, preferably by a ball and socket joint 15, Fig. 2. The rod 14 forms the piston rod for a motor, consisting preferably of a piston 16, Fig. 3, working in a cylinder 17 secured to a flange 18 on the casing 1.

Fluid pressure, preferably steam from the steam chest 2, is admitted to the cylinder 17 by a pilot valve operating in a casing 20 which is preferably cast integral with said cylinder. The steam enters at one side of the casing through a pipe 21, Fig. 2, and exhausts from the other side through a pipe 22 to the condenser conduit 6. A tubular plug 23 fills the interior of the casing 20. It has in one side a port 24, Fig. 4, admitting steam from the pipe 21 to its interior. The opposite side of the plug is flattened at 25 for a portion of its length and has two ports 26, 26' at the ends of said portion, entering the internal bore of said plug. Between these ports a port 27 in the casing connects the cutaway portion 25 with the exhaust pipe 22. Near each end of the motor

cylinder 17 are admission and exhaust ports 28, 28' which communicate with ports 29, 29' in the plug 23. A pilot valve having a stem 30 and two heads 31 thereon plays in the bore of the plug and controls the ports 29, 29'. The stem 30 is attached to a block 32 which is pivoted to a floating lever 33 fulcrumed at one end to an arm 34 on an extension 35 of the piston rod 14 of the motor. The other end of the floating lever is pivoted to an adjustable rod 36 which extends into a casing 37 fastened to the casing 20 and containing a movable abutment, such as a piston 38 attached to the rod 36. 15 A helical spring 39 abuts at one end against a shoulder on the casing and at the other end against a collar 40 on the rod 36. A nut 41 meshes with screw threads on said rod and bears against the collar. By rotating said 20 nut, the tension of the spring can be adjusted. A pipe 42 from the extraction stage (in this case the first) conveys the stage pressure to one side of the piston 38 and tends to move it in a direction opposite to 25 that in which the spring 39 biases it. From the space on the other side of said piston a pipe 43 runs to the condenser conduit 6.

The operation is as follows: The tension of the spring 39 is adjusted by the nut 41 30 so that it will balance the desired pressure of steam in the first stage 4 of the turbine from which steam is extracted through the outlet 3 for industrial purposes. Now suppose the demand for such steam lessens. 35 The stage pressure rises, the abutment 38 moves (to the right in Fig. 3), compresses the spring 39, and forces the lever 33 and the pilot valve to the right, thereby uncovering the ports 29' and 28' and admitting steam 40 from the pipe 21 to the right hand end of the cylinder 17. This drives the piston 16 to the left and pulls the annular valve wider open, so that a larger quantity of steam can overflow from stage 4 to stage 5 and thus 45 reduce the abnormal pressure in stage 4. In opening the ports 29' to steam the pilot valve connects the ports 28, 29 with the port 26, the cutaway portion 25, port 27 and exhaust pipe 22. The movement of the piston is 50 communicated by the rod 35, arm 34 and lever 33 to the pilot valve, drawing the latter back to its mid position and thereby cutting off the supply of steam to the cylinder 17, and locking the piston 16 in its new 55 position. It will thus be seen that the parts 33, 34 and 35 form a follow-up device. If the pilot valve has not moved very far, the piston 16 will be arrested before it has shifted very much from its former position. 60 If it should move to the end of its stroke, it will close the port 28 before it arrives at the end of the cylinder, so that a body of steam is trapped between the piston and the cylinder head and cushions the piston, preventing it from slamming. An increase in 65

the demand for industrial steam will produce an opposite effect, causing the motor to partly or wholly close the overflow valve in order to retain the steam in stage 4 and keep up its pressure.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. The combination with a multistage turbine, of a conduit for extracting steam from a stage of higher pressure, an annular overflow valve between said stage and the one next lower, a motor for opening and closing said valve, and means responsive to the steam pressure in said extraction stage for controlling said motor for the purpose of maintaining constant pressure in said stage.

2. The combination with a multistage turbine, of a gridiron overflow valve between stages, a motor for operating said valve, a pilot valve controlling said motor, a movable abutment for actuating the pilot valve and exposed to a higher stage pressure, a spring opposing said pressure on said abutment, and a pipe opening out of said higher stage for supplying steam for industrial purposes.

3. The combination with a multistage turbine, of an annular valve revoluble on a diaphragm and controlling the flow of steam to a lower stage, a motor for operating said valve, a pilot valve for said motor, a pipe connected to a stage of higher pressure through which steam flows, and a device responsive to variations in steam pressure in said stage of higher pressure for controlling said pilot valve.

4. The combination with a multistage turbine, of a conduit for steam connected to a stage of higher pressure, an annular valve controlling ports between said stage and the next lower, a piston motor for actuating said valve, a pilot valve controlling said motor, a piston working in a cylinder and exposed to the pressure in said higher stage, a spring opposing said pressure, and a floating lever pivotally connected to the piston pilot valve stem and the movable element of the motor.

5. The combination with a multistage turbine, of an annular gridiron valve revolubly mounted on a diaphragm between two stages and controlling the flow of steam to the nozzles of the next lower stage, a conduit extracting steam for industrial pur- 130

poses from the higher stage, and means responsive to the pressure in said higher stage for opening and closing said valve.

6. A turbine comprising a casing that is divided by a diaphragm into stages of different pressures, rotors for the stages, devices admitting steam to the said rotors, a conduit extracting steam from the stage of higher pressure, a valve that controls a number of the nozzles admitting steam to the rotor of lower pressure, a motor, a connection between the movable part of the motor and the valve, a pilot valve for the motor, and a device responsive to the pressure in the extraction stage for moving the pilot valve.

7. The combination with a multistage turbine, of a conduit for extracting steam from a stage of higher pressure, an overflow valve between said stage and the next lower, a motor for operating said valve, having a piston and piston rod, a lever pivotally connected to the piston rod, a pilot valve for said motor having its stem pivoted to said lever, and a movable abutment piv-

otally connected to the end of said lever and responsive to variations in steam pressure in the extraction stage.

8. The combination with a multistage turbine, of a conduit for extracting steam from a stage of higher pressure, an overflow valve between said stage and the next lower, a motor for operating said valve having a piston and piston rod, an extension of said rod passing through the head of the motor cylinder, an arm on said extension, a lever fulcrumed on said arm, a pilot valve for the motor having its stem pivotally connected to said lever, a movable abutment pivotally connected to the end of said lever and exposed to the steam pressure in the extraction stage, and yielding means for opposing said pressure.

In witness whereof, I have hereunto set my hand this ninth day of January, 1913. 45

FRED E. NORTON.
